CLUTCHED DRIVING MEANS FOR TOOLS

Roy E. Gearhart, Kansas City, Mo., assignor of
one-half to Charles E. Hose, Kansas City, Mo.

Application May 23, 1949, Serial No. 94,835

8 Claims. (Cl. 81—58)

1

This invention relates to new and useful improvements in clutch tools, and has particular reference to tools of the class including wrenches and screw drivers.

In using tools such as wrenches or screw drivers it is often desirable to turn an object such as a nut or bolt or screw in one direction only while turning the tool reciprocally, without disengaging the tool from the object being turned. This object is ordinarily accomplished by "ratchet" wrenches or screw drivers. The principal object of the present invention is the provision of a tool of this class having numerous advantages over the usual "ratchet" type tools.

Another object is the provision of a tool of the class described having a manually operable driver handle, and a work engaging member, co-operating clutch members carried respectively by said handle and work engaging member, said clutch members being so related that a slight relative movement of said handle and work engaging member in a direction transverse to the direction of rotation of the tool will cause an initial engagement of said clutch members, and means operable when said handle is turned in either direction to force said clutch members into full engagement.

A further object is the provision, in a tool of the class described, of means adapting the tool to rotate objects in either direction without the operation of external switching levers or the like.

A still further object is the provision in a tool of the character described, of a pair of circular toothed clutch members adapted to mesh together around their entire peripheries, whereby the clutch members will function efficiently even though a considerable number of the teeth are broken or damaged.

Other objects are simplicity and economy of construction, ease and convenience of operation, durability, adaptability to be used in tools of very small size, and adaptability to be used in tools of various types.

With these objects in view, as well as other objects which will appear in the course of the specification, reference will be had to the drawing, wherein:

Figure 1 is a side elevation of a clutch wrench embodying the present invention, with parts broken away.

Fig. 2 is an edge view of the wrench shown in Fig. 1.

Fig. 3 is an enlarged fragmentary section taken on line III—III of Fig. 2, with the wrench socket member omitted.

2

Fig. 4 is a section taken on line IV—IV of Fig. 3.

Fig. 5 is an irregular section taken on line V—V of Fig. 3, showing a face view of the operating cams fixed in the body member.

Fig. 6 is an irregular section also taken on line V—V of Fig. 3, but looking in the opposite direction, showing a face view of the cams and stops carried by the floating clutch member.

Fig. 7 is a fragmentary section taken on line VII—VII of Fig. 6, showing the toothed clutch members in their normal, disengaged relationship.

Fig. 8 is a view similar to Fig. 7, showing the clutch members brought into partial engagement by axial movement of the face plate.

Fig. 9 is a view similar to Fig. 7, showing the clutch members brought into full engagement by the action of the operating cams.

Fig. 10 is a side elevation of a screw driver embodying the present invention.

Fig. 11 is an enlarged fragmentary section taken on line XI—XI of Fig. 10.

Like reference numerals apply to similar parts throughout the several views, and in the wrench shown in Figs. 1 to 9, the numeral 2 applies to a hollow, cylindrical body member closed at one end by wall 4 and having a radially extending handle 6 welded or otherwise rigidly attached thereto. A flat cylindrical face plate 8 is carried for rotation and axial sliding movement in the open end portion of body member 2. The portion of said face member is provided with a radial flange 10 adapted to abut against body member 2 to limit the inward sliding movement of the face plate. Said face plate is formed to present an outwardly extending axial stem 12, preferably square in cross-section, adapted to fit into a correspondingly shaped hole 14 formed in an ordinary wrench socket member 16. Said socket member is retained on said stem by a detent ball 18 embedded in a recess 20 formed in stem 12 and urged outwardly by a spring 22 carried in said recess. Said ball is adapted to engage a recess 24 formed in the wall of hole 14. Socket member 16 has a non-circular socket 26 formed in its outer end for engaging nuts, bolt heads, and the like. Said socket members of course are usually sold in sets, having sockets of graduated sizes and different shapes. This type of socket, and its mounting, is common and no claim is made specifically thereto.

A plurality of teeth 28 are formed on the inner surface 30 of face plate 8, said teeth being equally spaced about the periphery of said face plate and

projecting parallel to the axis of body member 2. Said face plate is thereby adapted to function as a clutch member. Said face plate is also provided with a cylindrical shank 32 which extends axially through body member 2 and which is carried for rotation and axial sliding movement in an inwardly projecting bearing tube 34 formed integrally with body member wall 4. A screw 36 is threaded axially into the free end of said shank. The head 38 is disposed rotatably in a countersunk hole 40 formed in the outer surface of wall 4. Said head abuts against the end of shank 32, and also against an outwardly facing shoulder 42, formed at the bottom of hole 40, thereby limiting the outward sliding movement of face plate 8. It will be noted that flange 10 is normally spaced apart from body member 2, the clearance 44 therebetween permitting a very limited axial movement of the face plate in the body member.

Welded or otherwise fixed in body member 2 within the annular space between bearing tube 34 and the cylindrical wall of said body member, are a pair of like operating cams 46, best shown in Figs. 5, 7, 8 and 9. Said cams are disposed in diametrically opposite sides of the housing, and each has substantially the shape of a segment of a flat annular ring. The outer surface of each of said cams, or the lower surface as viewed in Figs. 7, 8, and 9, is formed to present a substantially V-shaped groove 48 disposed radially to the body member. Said cam is formed to present flat dwell surfaces 50 adjacent each side of said groove. The end surfaces 52 and 54 of said cams are radially disposed and parallel to the axis of the body member and serve as stops as hereinafter described.

A floating clutch member 56 is carried for rotation and axial sliding movement on shank 32 between face plate 8 and body wall 4. Said clutch member has the form of a flat gear having radially projecting teeth 58 equally spaced around the periphery thereof. Said teeth are adapted to mesh with teeth 28 of face plate 8, as said clutch member is moved axially toward said face plate along shank 32. On the surface of clutch member 56 adjacent body wall 4 are formed a pair of like cams 60. Said cams are disposed on diametrically opposite sides of the axis of the clutch member, and are substantially V-shaped in order to mesh with V-grooves 48 of operating cams 46, as best shown in Figs. 7 and 8. Each of cams 60 is provided at its apex with a flat dwell surface 62. A pair of stop members 64 are also formed on clutch member 56. Said stop members are segments of annular rings, and are disposed at diametrically opposite sides of the clutch member, ninety degrees removed from cams 60, and are adapted to project between operating cams 46. The end surfaces 66 and 68 of said stop members are disposed radially and parallel with the axis of the body member, and cooperate with surfaces 52 and 54 of operating cams 46 as hereinafter described. A helical spring 69 is disposed about shank 32, bearing at one end in a circular groove 70 formed in clutch member 56, and at its opposite end in a similar groove 72 formed in inner surface 30 of face plate 8. Said spring functions to urge face plate 8 and clutch member 56 apart to keep teeth 58 and teeth 28 out of engagement and to urge face plate 8 to the outer limit of its axial movement.

The operation of the wrench is substantially as follows: When socket member 16 is positioned over a nut or the like which is to be turned, face

plate 8 is in effect directly coupled to the nut. Body member 2, however, can be freely rotated in either direction without turning said face plate, as long as the parts have the relative positions shown in Figs. 3 and 8 since clutch teeth 28 and 58 are out of engagement. Clutch member 56, by reason of the engagement of cams 60 in cams 46, turns with the body member. The operator, while turning the body member in the direction desired by means of handle 6 exerts a slight pressure axially on the body member, thereby forcing face plate 8 inwardly relative to the body member, against the pressure of spring 68, until flange 10 of said face plate strikes the body member. Since the clearance 44 between said flange and body member is slightly greater than the clearance between teeth 28 and teeth 58, this relative axial movement causes a slight meshing of said teeth, as clearly shown in Fig. 8. Since there is a substantially large number of teeth in the circumference of the toothed members, they may also mesh at numerous points in each revolution, and there will hence be very little lost motion before said meshing occurs.

Clutch member 56 is thereby secured against rotation relative to face plate 8. Further rotation of body member 2 by the operator causes operating cams 46 to force cam 60 and clutch member 56 axially toward face plate 8, thereby moving teeth 58 of said clutch member into full engagement with teeth 28 of said face plate, as shown in Fig. 9. When cams 60 have been forced all the way out of grooves 48 of cams 46, dwells 62 of cam 60 contacts one of dwells 50 of cam 46, thereby securing the clutch teeth in the engaged position. At the same time, cams 46 strike stops 64, whereby rotation of body member 2 relative to clutch member 56 is arrested. For example, when the body member is turned clockwise as viewed in Fig. 6, stop surfaces 56 of cams 46 strike stop surfaces 66 of stops 64. If the body member were turned in a counterclockwise direction, surfaces 54 of cams 46 would strike surfaces 68 of stops 64.

Any torque exerted on handle 6 by the operator will be transmitted directly to clutch member 56 by cams 46, from said clutch member to face plate 8 by means of teeth 58 and 28, and from said face plate to socket member 16 by means of stem 12. Reversing the movement of handle 46 will move cam groove 48 over cams 60, whereupon spring 68 will separate clutch member 56 from teeth 28 of the face plate, to permit free reverse rotation of the body member.

It will be noted in Fig. 9 that cams 46 do not push clutch member 56 tightly against face plate 8. There is a slight axial clearance between these members even when these respective teeth are engaged. This removes any axial stress from assembly screw 36, and prevents any tendency for said screw to become loosened during normal operation. It will be noted also that since no substantial torque can be transmitted from clutch member 56 to face plate 8 until cams 46 strike stops 64, teeth 28 and 58 are fully engaged before they are required to transmit the full load being applied to the tool. This permits easy engagement of the teeth, and tends to prevent tooth breakage and damage.

Figs. 10 and 11 show a screw driver embodying the present invention. Body member 74 of the screw driver, which corresponds to body member 2 of the wrench, is substantially similar to body member 2 except that it is provided with a rearwardly extending circular wall 76 which

forms a socket for receiving an axially projecting handle 78, said handle being secured in said socket by rivet 80. Face plate 82, which corresponds with face plate 8 of the wrench, is substantially similar to face plate 8, except that in place of stem 12, it carries an axial bit 84 shaped at its outer end to form a screw driver blade 86. All other parts of the screw driver are similar in construction and operation to corresponding parts of the wrench. The inner end of handle 78 may be recessed as at 88 to permit the necessary axial movement of screw head 38.

Thus it is apparent that a clutch-type tool having several advantages has been produced. It will function in the manner of a ratchet-type tool to turn work in one direction only as the tool itself is reciprocated, and may be reversed to turn the work in the opposite direction without operation of a reversing lever or the like. By positioning the parts so that dwells 62 of cams 60 engage dwells 50 of cams 46, the clutch may be secured in the engaged position to turn work in either direction. Because of the multiple tooth engagement of the clutch, it will continue to function efficiently even after a considerable number of teeth are broken. The clutch mechanism is particularly adapted for use in tools of very small diameter, hence providing a tool adapted for use in inaccessible, cramped quarters.

Although I have disclosed specific embodiments of my invention, it is apparent that many minor modifications of construction could be made without departing from the spirit of the invention.

What I claim is:

1. A clutch tool comprising a body member, a handle by means of which said body member may be rotated, a first toothed clutch member carried for rotational and axial movement by said body member, a work engaging member fixed to said clutch member, a second toothed clutch member carried for axial and limited rotational movement by said body member, said clutch members being adapted to be partially engaged by axial movement of said first clutch member, and cooperating cams carried respectively by said body member and said second clutch member, whereby said second clutch member is moved axially into full engagement with said first clutch member, said cams having dwells whereby said clutch members may be retained in the engaged position.

2. A clutch tool comprising a body member, a handle by means of which said body member may be rotated, a first toothed clutch member carried for rotational and axial movement by said body member, a work engaging member fixed to said clutch member, a second toothed clutch member carried for axial and rotational movement by said body member, said clutch members being adapted to be partially engaged by axial movement of said first clutch member, means operable by the relative rotational movement of said body member and said second clutch member axially into full engagement with said first clutch member, and stops adapted to arrest the relative rotation between said second clutch member and said body member when said clutch members are fully engaged.

3. A clutch tool comprising a body member, a handle by means of which said body member may be rotated, a first toothed clutch member carried for rotational and axial movement by said body member, a work engaging member fixed to said clutch member, a second toothed clutch mem-

ber carried for axial and rotational movement by said body member, said clutch members being adapted to be partially engaged by axial movement of said first clutch member, cooperating cams fixed respectively to said body member and said second clutch member, whereby said second clutch member is moved axially into full engagement with said first clutch member when said body member is rotated in either direction relative to said second clutch member, said cams having dwells whereby said clutch members may be retained in the engaged position, and stops for arresting the relative rotation of said body member and said second clutch member when said clutch members are fully engaged.

4. A clutch tool comprising a body member, a handle by means of which said body member may be rotated, a first toothed clutch member carried for rotational and axial movement by said body member, a work engaging member fixed to said clutch member, a second toothed clutch member carried for axial and rotational movement by said body member, said clutch members being adapted to be partially engaged by axial movement of said first clutch member, means operable by the relative rotational movement of said body member and said second clutch member axially into full engagement with said first clutch member, and stops adapted to arrest the relative rotation between said second clutch member and said body member when said clutch members are fully engaged, the parts being so proportioned as to provide a slight axial clearance between said first and second clutch members when the teeth of said clutch members are fully engaged.

5. A clutch tool comprising a hollow cylindrical body member, a handle by means of which said body member may be axially rotated, a first clutch member carried for rotation in said body member and adapted to be manually moved axially in said body member, stops limiting the axial movement of said clutch member, a work engaging member fixed to said clutch member, a second clutch member carried for rotational and limited axial movement in said body member, said clutch members having matching peripheral teeth adapted to be engaged by relative axial movement of said clutch members, resilient means normally holding said clutch members apart, said clutch members being adapted to be partially engaged by manually moving said first clutch member to the inner limit of its axial travel, and cooperating cams carried respectively by said body member and said second clutch member whereby relative rotation of said members in either direction will move said second clutch member axially into full engagement with said first clutch member.

6. A clutch tool comprising a hollow cylindrical body member, a handle by means of which said body member may be axially rotated, a first clutch member carried for rotation in said body member and adapted to be manually moved axially in said body member, stops limiting the axial movement of said clutch member, a work engaging member fixed to said clutch member, a second clutch member carried for rotational and limited axial movement in said body member, said clutch members having matching peripheral teeth adapted to be engaged by relative axial movement of said clutch members, a spring disposed between said clutch members and adapted normally to maintain said clutch members out of engagement and to maintain said

first clutch member at the outer limit of its axial travel, said clutch members being adapted to be partially engaged by manually moving said first clutch member to the inner limit of its axial travel, and cooperating cams carried respectively by said body member and said second clutch member, whereby relative rotation of said members in either direction will move said second clutch member axially into full engagement with said first clutch member.

7. A clutch tool comprising a hollow cylindrical body member, a handle by means of which said body member may be axially rotated, a first clutch member carried for rotation in said body member and adapted to be manually moved axially in said body member, stops limiting the axial movement of said clutch member, a work engaging member fixed to said clutch member, a second clutch member carried for rotational and axial movement in said body member, said clutch members having matching peripheral teeth adapted to be engaged by relative axial movement of said clutch members, resilient means normally holding said clutch members apart, said clutch members being adapted to be partially engaged by manually moving said first clutch member to the inner limit of its axial travel, cooperating cams carried respectively by said body member and said second clutch member, whereby relative rotation of said members in either direction will move said second clutch member axially into full engagement with said first clutch member, and stops for arresting the relative rotation of said body member and said second clutch member when said clutch members are fully engaged.

8. A clutch tool comprising a hollow cylindrical body member, a handle by means of which said body member may be axially rotated, a first clutch member carried for rotation in said body

member and adapted to be manually moved axially in said body member, stops limiting the axial movement of said clutch member, a work engaging member fixed to said clutch member, a second clutch member carried for rotational and axial movement in said body member, said clutch members having matching peripheral teeth adapted to be engaged by relative axial movement of said clutch members, resilient means normally holding said clutch members apart, said clutch members being adapted to be partially engaged by manually moving said first clutch member to the inner limit of its axial travel, cooperating cams carried respectively by said body member and said second clutch member, whereby relative rotation of said members in either direction will move said second clutch member axially into full engagement with said first clutch member, and stops for arresting the relative rotation of said body member and said second clutch member when said clutch members are fully engaged, said cooperating cams having dwells which come into matching relation as said stops become operative, whereby said clutch members are secured in the engaged position.
